CLAIM

The ornamental design for a wall mounted guitar holder, as shown and described.

DESCRIPTION

FIG. 1 is a front and top perspective view of a wall mounted guitar holder showing my new design, and shown in association with guitars, depicted in phantom outline, and not a part of this invention;

FIG. 2 is a side view thereof, taken from the right of FIG. 1;

FIG. 3 is a top view thereof;

FIG. 4 is a bottom view thereof; and,

FIG. 5 is a front view thereof.
